UNITED STATES PATENT OFFICE.

WILLIAM W. BOYLE AND FRANK MILLER, OF ST. JAMES, MICHIGAN.

FURNITURE-FASTENING.

1,111,209.

Specification of Letters Patent. Patented Sept. 22, 1914.

Application filed June 26, 1913. Serial No. 775,961.

To all whom it may concern:

Be it known that we, WILLIAM W. BOYLE and FRANK MILLER, citizens of the United States, residing at St. James, in the county 5 of Charlevoix and State of Michigan, have invented new and useful Improvements in Furniture-Fastenings, of which the following is a specification.

Our present invention pertains to furniture, and contemplates the provision of peculiar and advantageous means for connecting mirror and other superposed frames to dressers and other articles of furniture, and this in such manner that the connection is a 10 strong and rigid one, and yet when it is desired to remove the frame, the same can be expeditedly and easily accomplished without the employment of tools.

With the foregoing in mind, the invention will be fully understood from the following description and claim when the same are read in connection with the drawings, accompanying and forming part of this specification, in which:

25 Figure 1 is a rear elevation of an article of furniture equipped with our novel device. Fig. 2 is a detail horizontal section taken in a plane above one of the fasteners. Fig. 3 is a plan of one of the fastener members to be attached to the superposed frame. Fig. 4 is an edge elevation of one of the fastener members on the back of the body of the article of furniture.

Similar numerals of reference designate 35 corresponding parts in all of the views of the drawings.

In the illustrated embodiment of our invention a mirror frame 1 is superposed on a dresser 2 or other article of furniture in the 40 ordinary, well known manner.

Permanently fixed to the back of the furniture article 2 are fastener members 3 having enlarged upper portions 4, and pivotally connected at 5 to the said enlarged portions 45 4 are the enlarged portions 6 of members 7 which are arranged to be swung in a plane parallel to the back of the article 2. The said members 7 are preferably, though not necessarily, recessed as illustrated, in 50 order to contribute to the compactness of the fasteners.

Fixed at 8 to the back of the mirror or other frame 1, are fastener members 9, disposed horizontally, and having inner offset 55 portions 10 between which and the back of the furniture article the swinging members

are adapted to rest when said swinging members are in upright positions.

Disposed at the outer sides of the offset portions 10 of members 9 are spring strips 60 11, connected at 12 to said offset portions, and carried at the free ends of said spring strips are beveled heads 13. The said spring strips 11 and heads 13 constitute spring latches for holding the swinging members 7 65 in engagement with the members 9 to secure the frame 1 on the furniture article 2.

With the parts relatively arranged as shown in Fig. 1, it will be manifest that the frame 1 will be securely and rigidly held on 70 the article 2. When, however, it is desired to detach and remove the frame 1, it is simply necessary to draw the heads 13 of the spring strips in a direction away from the back of the article 2 and then swing 75 the members 7 inwardly and downwardly in a plane parallel to the back of the article 2. It will also be here noted that when so swung inwardly and downwardly, the members 7 will be out of the way and will not 80 be liable to breakage or injury when the piece of furniture is moved.

To fasten the frame 1 on the article 2 in accordance with my invention, it is simply necessary to correctly position the frame 1, 85 and then swing the members 7 upwardly and outwardly until they snap by the heads 13 of the strips 11 and assume positions between the offset portions 10 and the back of the article 2, when the frame 1 will be safely 90 and strongly locked to the article 2.

In the mounting of the mirror we prefer to employ hook-shaped bearings 25 on the uprights of the frame 1, in combination with notched trunnions 26 fixed with respect to 95 the mirror and disposed in bearings 25 so that said bearings rest in the said notches. With the bearings and trunnions thus relatively arranged it will be manifest that the mirror will be strongly and safely supported 100 in such manner that the mirror will be free to swing but will be effectually held against endwise play; also, that the mirror may be readily removed by merely lifting the trunnions 26 from the bearings 25.

Having described our invention, what we claim and desire to secure by Letters Patent, is:

The combination of superposed furniture parts, a fastener member pivotally connected 110 with the back of one part and constructed and arranged to swing vertically in a plane

parallel to said back and behind the back of the other part; a fastener member fixed in horizontal position to the back of such other part and having its inner portion offset from 5 said back to afford a space for the reception of the first-named member when swung vertically, and a spring strip carried at the outer side of the offset portion of the second-named member and having a beveled head disposed beyond the inner end of said offset portion; said head being arranged to 10 permit of movement of the first-named

member past it and to confine said fastener member in the space between the offset portion of the second-named fastener member 15 and the part to which said member is fixed.

In testimony whereof we have hereunto set our hands in presence of two subscribing witnesses.

WM. W. BOYLE.
FRANK MILLER.
